United States Patent

Des. 236,819
Patented Sept. 16, 1975

236,819

FRAME FOR A RAILROAD RAIL GRINDING MACHINE

Willard J. Duecker, Stockton, Calif., assignor to
Colberg, Inc.

Filed June 10, 1974, Ser. No. 478,073

Term of patent 14 years

Int. Cl. D12—03

U.S. Cl. D12—42

FIG-2

FIG. 3

FIG. 4

FIG. 5

FIG. 1 is an isometric view of a frame for a railroad rail grinding machine showing my new design.

FIG. 2 is a top plan view thereof.

FIG. 3 is a side elevational view thereof.

FIG. 4 is an end elevational view thereof.

FIG. 5 is an end elevational view thereof opposite to that shown in FIG. 4.

I claim:

The ornamental design for a railroad rail grinding machine, as shown.
